METHOD OF AND MACHINE FOR LASTING SHOES

Benjamin B. Blanchard, Swampscott, Mass., assignor to United Shoe Machinery Corporation, Flemington, N. J., a corporation of New Jersey

Application August 28, 1945, Serial No. 613,041

25 Claims. (Cl. 12—2)

1

This invention relates to fastening inserting machines and methods and is herein illustrated as applied to a machine of the type disclosed in United States Letters Patent No. 1,815,295, granted July 21, 1931, on an application filed in the name of George Goddu, this machine being particularly adapted to secure a shoe upper, after it has been tensioned over a last, in lasted relation to a sole member on the last bottom by means of metallic fastenings, such as wire staples. It is to be understood that in its more general aspects the invention is not limited to use in machines of that particular character nor to the manufacture of shoes.

In the machine of the above mentioned Letters Patent, a staple is formed from a piece of wire and thereafter is inserted through the overlasted marginal portion of the upper into the sole member without penetrating the entire thickness of the latter. This condition, which is desirable since the points of the staple legs do not enter the inside of the shoe, is obtained by progressively bending the staple legs during the driving operation to cause the staple legs to follow curved paths in the sole and to curl back toward the face of the sole from which they entered it. The staple legs are bent by a deflector which, in the machine of the above mentioned patent, is located on the side of the sole whence the staple is driven and serves to curve successive portions of the staple legs before they enter the sole.

It is an object of the present invention to improve upon the construction and operation of machines of the above mentioned type, particularly to insure that each staple is so inserted that its crossbar is firmly embedded in the work (in the present case the marginal portion of the shoe upper) without the danger of the deflector impeding, due to its position, such complete insertion of each staple by the staple driver.

To this end and in accordance with a feature of the invention, the illustrated machine is provided, in addition to shoe upper tensioning means, such as a gripper and wiping means for laying the marginal portion of the upper inwardly over the sole, with upper fastening means including a staple driver and a staple deflector, the arrangement being such that the deflector, prior to the insertion of the staple, is caused to enter the substance of the work and serves to bend the staple legs progressively within the substance of the work and after the staple legs have entered the work. This construction insures that each staple is fully inserted into the work with its crossbar embedded in the work surface, since the driver

2

no longer is prevented by the deflector from moving down to the surface of the work to drive the staple bar "home." At the same time this construction in no way disturbs the accuracy of cooperation between the driver and the deflector essential for inserting each staple in a predetermined path in the work.

More specifically, the driver and the deflector are carried by a common supporting member into 10 a position from which they are operated in predetermined directions and in time relation to each other and the operation of both is effected by a common member which, in the illustrated example, is a lever having connections to additional levers adapted to operate the deflector and the driver. This insures uniformity of operation and accuracy of timing.

In accordance with another feature of the invention, the staple deflector comprises two awl-like prongs which enter the work prior to the driving of the staple at a location in which the prongs can guide and deflect the staple legs after the latter have entered the work, the deflector thus, by reason of its positive engagement with 20 the work, effectively holding the work against the operating thrust of the driver. Moreover, since the deflector in entering the work penetrates through the tensioned marginal portion of the upper and enters the sole, the deflector serves the 25 additional purpose of positively holding the tensioned marginal portion of the upper under stress in lasted relation to the sole member before the staple is inserted to secure the upper in lasted position.

30 Thus, in another aspect, the invention finds expression in a novel method of making shoes, particularly lasting shoes according to which the marginal portion of the upper, after it has been tensioned and laid over the margin of the sole member is immediately secured in lasted position by the deflector which is inserted through it and into the sole. As a result, the benefit of the lasting operation is not even partly lost due to any 35 possible slip back of the marginal portion of the upper after the opening of the lasting gripper and prior to the driving of a staple.

These and other features of the invention are described in detail in the following specification 40 in connection with the accompanying drawings and are pointed out in the appended claims.

In the drawings,

Fig. 1 is a left hand side elevation of part of 45 the head portion of a machine in which the novel features of the invention are embodied, certain

parts being shown in section and other parts being broken away;

Fig. 2 is a front elevation of the structure shown in Fig. 1, certain parts being broken away;

Fig. 3 is an angular view of the staple deflector mechanism and associated operating parts;

Fig. 4 is a detail view, in left hand elevation, of part of the structure shown in Fig. 1; and

Fig. 5 is a right hand side elevation of mechanism for adjusting the staple deflector.

The illustrated machine in its organization is, except for the construction of portions of the staple driving mechanism and the construction and operation of the staple deflector mechanism, similar to the machine disclosed in the aforementioned Letters Patent. Accordingly, only such features of the general organization as it is necessary to refer to for an understanding of the invention will be described herein in detail.

It is the purpose of the illustrated machine to tension a shoe upper A (Fig. 4) over a last B carrying a sole member C (e. g. an insole) on its bottom, to lay the marginal portion of the tensioned upper over and against the plane bottom face of the sole member and to secure the overlaid marginal portion of the upper in lasted relation to the sole member by staples D. To this end, the machine is provided with a gripper 16 (Figs. 1 and 4) adapted to pull the upper heightwise of the last and inwardly over the sole member, and upper fastening mechanism, including a staple driver and a staple deflector, adapted to lay the marginal portion of the tensioned upper inwardly over the sole member and to secure that marginal portion in lasted position. The construction of the gripper mechanism is the same as that of the corresponding mechanism disclosed in or referred to in the above mentioned patent.

To assist the operator in positioning the work piece, that is the last B provided with the sole member C and carrying the shoe upper A, in proper relation to the operating instrumentalities of the machine, there are provided an edge gage 12, adjustable heightwise as well as forwardly and rearwardly in the machine, and a similarly adjustable bottom rest 14.

The upper fastening mechanism, including means for forming staples above the line of drive and for transferring them into alignment with the staple driver, is for the most part movable bodily toward and from the work piece in directions inclined to the bottom face of the sole member C and the movement toward the work piece is utilized to lay the marginal portion of the upper inwardly over the insole into position to be fastened. Secured to the head of the machine is a supporting member 16 (Fig. 1) provided with a forwardly and downwardly inclined guideway for a slide 18, this slide having mounted thereon the staple transferring, driving and deflecting mechanisms and a portion of the staple forming mechanism. For moving the slide 18 along its guideway toward and from the work piece, the slide carries a cam roll 20 engaging a cam groove in a cam disk (not shown) mounted on a cam shaft (not shown) of the machine.

The staple is formed from a piece of wire (which is the front end portion of a wire strand) after this piece of wire has been fed into the staple forming mechanism by wire feeding mechanism (not shown), and severed from the wire strand by wire severing mechanism (not shown). The wire severing, staple forming and staple transferring mechanisms with which the present machine is provided are the same as the corre-

sponding mechanisms of the machine disclosed in the above mentioned patent. These mechanisms in part are mounted on a bracket 22 (Figs. 1 and 4) integral with the front portion of the supporting member 16 and in part are mounted on a bracket 24 secured to the lower front end portion of the slide 18 by screws 26. The wire is advanced by the wire feeding mechanism through a flexible conduit 28 (Fig. 4) to a wire nozzle comprising blocks 30 secured by a screw 32 on an upwardly extending part of the bracket 24. The wire is fed through an outside staple former (not shown) supported on the bracket 22 on which is also provided a severing knife (not shown). After the wire has been fed through the outside staple former, the slide 18 is caused to move downwardly and forwardly in the machine toward the shoe presented to the machine with the result that the front end portion of the wire strand is severed. An inside staple former (not shown) mounted on the bracket 24 engages, as a result of the forward movement of the slide 18, the severed piece of wire and pushes it into the outside former to form a staple. Thereafter, the staple transferring mechanism becomes active to move the formed staple into staple driving position. The staple is moved by a transferring member 34 (Fig. 1) which is mounted for movement heightwise of the machine in the slide 18 and which is actuated by a cam operated bar 36. The staple when moved into driving position is tilted by the transferring member 34 and lowered into a throat which, in construction and function, is like the throat or nozzle of the machine of the above mentioned patent. The throat comprises plates 38 (Fig. 4) secured in opposed relation by screws 40 to plates 42 which are fastened together side by side by a screw 44. The plates 42 are provided at their upper ends with flanges 46 which are fastened by screws 48 to the bracket 24 on the slide 18. The plates 38 are shaped to extend inwardly under the lower edges of the plates 42 and to provide a guideway for a staple driver, to be described, which is T-shaped in cross section. The flanges 46 are provided with upturned portions 50 through which are threaded screws 52, the screws abutting against the bracket 24 and being held in place by locknuts 54.

The staple driving mechanism comprises a driver 56 (Figs. 1 and 4), already mentioned, which is reciprocated in the guideway formed by the plates 38 by mechanism to be described. The driver 56 extends into and is movable with relation to a casing 58 (Fig. 1) that contains a driver clamping mechanism and a part of the driver actuating mechanism. The casing 58 is secured by screw bolts 60 to a forward extension 62 of the slide 18, the casing 58 and driver thus participating in the movements of the slide 18. The lower end of the casing 58 is provided with a rearward extension 64 engaging a notch provided in the plates 38 and 42 to give additional support to the casing 58. Moreover, the extension 64 has parallel flanges 66 engaging the outsides of the plates 42. The driver 56 extends into a substantially rectangular block 68 which has a sliding fit in the casing 58 and is provided with a bore shaped to accommodate the driver. The block 68 is recessed at its forward end to admit a clamping screw 70 which serves to secure the driver 56 to the block 68. The block 68 is also provided with a spherical recess forming a socket in which is received a ball 72 bored diametrically so that the driver can be extended through it and having heightwise extending grooves at opposite

sides thereof which are engaged by the bifurcated lower end of a small arm 74 extending through an aperture into the casing 58 and being adjustably secured to a driver operating lever 76. The driver 56 thus is fulcrumed on the arm 74. The driver operating lever 76 is rotatably mounted on a shaft 78 (Figs. 1 and 2) extending through the forward extension 62 of the slide 18 and secured against rotation. More specifically, the driver operating lever 76 is mounted on a sleeve 80 on the shaft 78. The sleeve has a flange 82 abutting the slide extension 62 and carrying locking pins 84 engaging holes in the extension 62 to hold the sleeve 80 against rotation and to permit the tightening of a locknut 86 on the shaft 78 which holds the sleeve 80 and thus the lever 76 in place. On the opposite side of the slide extension 62 the shaft 78 has a flange 88 carrying locking pins 90 engaging holes in the slide extension 62, thus to immobilize the shaft 78.

To rock the driver operating lever 76 about the shaft 78, thereby to reciprocate the driver 56, there is provided an operating member in the form of a bell crank lever 92 fulcrumed on a shaft 94 mounted in the slide 18. The bell crank lever 92 has a forwardly extending arm carrying a cam roll 96 which engages a cam track 98 provided in the driver operating lever 76. Downward movement of the cam roll 96 in the cam track 98 causes a swinging movement of the lever 76 in a counterclockwise direction as viewed in Fig. 1, as a result of which the driver 56 is retracted. On the other hand, upward movement of the cam roll 96 causes a rotation of the lever 76 in a clockwise direction, as a result of which the driver 56 is moved toward the shoe to insert a staple therein. The cam track 98 is so shaped that at the beginning of the upward movement of the roll 96 therein there is a short dwell in the movement of the lever 76, for a purpose to be described. The bell crank lever 92 is spring operated to impart to the driver 56 its driving stroke. To this end there is mounted on the hub portion 100 of the bell crank lever 92 a torsion spring 102 one end of which engages a lug 104 on a downwardly extending arm 106 of the bell crank lever 92 and the other end of which engages a portion of the slide 18. As in the machine of the above mentioned patent the slide 18, after having moved downwardly and forwardly and after the driver has been operated, is retracted with the driver in its lowermost position. During the retraction the downwardly extending arm 106 of the bell crank lever 92 is caused to become locked. To this end the arm 106 is provided with a latch plate 108 which is engaged by a latch 110 pivotally secured on a cam operated lever 112 rotatably mounted on the machine frame, the latch 110 being biased by a spring 114 which tends to swing the latch 110 about its pivot into latching position. After the latch 110 has engaged the latch plate 108 and when the slide is again advanced downwardly toward the shoe bottom, the bell crank lever 92, due to its latching engagement with the lever 112, is rotated in a clockwise direction (Fig. 1), thereby loading the spring 102. After the slide 18 has arrived in its forward operative position a trip screw 116, secured in a lug of the slide 18, has been moved into the immediate vicinity of an upwardly extending arm 118 of the latch 110. However, the latch 110 is not tripped to free the bell crank lever 92 by the screw 116 pushing against the arm 118 of the latch 110 but rather the lever 112 which carries the latch 110 is operated by its cam (not shown) to cause the arm 118

to abut the screw 116, thereby tripping the latch 110 and releasing the bell crank lever 92 to the force of its spring 102. The reason for this arrangement is to time the operation of the driver 56 to occur somewhat after the slide 18 has arrived in its operative position to enable the staple forming and transferring mechanisms to form the staple and transfer it into driving position. Rotating the bell crank lever 92 in a clockwise direction, as viewed in Fig. 1, thereby loading the spring 102, as above described, results in a downward movement of the cam roll 96 in the cam track 98 in the cam lever 76 so that the driver 56 is withdrawn. Tripping the latch 110 causes a quick upward movement of the cam roll 96 as a result of which the driver 56 is propelled downward to drive the staple into the work with the bar of the staple parallel to the sole edge.

To cause the staple, when being driven, to follow a curved path in the work so that the staple curls back toward the surface of the sole member C whence it was driven, without penetrating the entire thickness of the sole member, the staple legs are progressively bent or deflected during the driving operation. To this end there is provided a deflector 120 (Figs. 1-4) comprising a bifurcated awl-like member which is arranged to enter the work, that is to say to pierce the overlaid marginal portion of the upper and to penetrate part way into the sole member C, as illustrated in Fig. 4 of the drawings. The deflector 120 is caused to enter the work at a point opposite the outlet end of the throat where the staple emerges when being driven by the driver 56. The two prongs 122 of the deflector 120 have grooves, as illustrated best in Fig. 3, which are curved and which are engaged by the staple legs after the latter have entered the work. The grooves serve to curve or bend the staple legs laterally of the crossbar of the staple so as to make the staple curl away from the edge of the sole member C and back toward the surface of the work whence the staple entered (see Fig. 4). The deflector 120 is mounted to move heightwise of the machine into and out of engagement with the work in a direction substantially normal to the work surface, whereas the driver 56 moves in a direction inclined at an acute angle toward and from the work surface, the driver when on its operative stroke moving inwardly of the machine and outwardly of the bottom of the shoe toward the adjacent edge of the sole member. Moreover, the deflector 120, as will be described, also is mounted to move with the slide 18.

The deflector 120 is mounted in the machine as follows: The upper part of the deflector is block-shaped and has an upwardly extending stem 124 (Fig. 3) which fits into an axially extending bore provided in a plunger 126 to which it is secured by a pin 128 so that deflector 120 and plunger 126 may move as a unit heightwise of the machine. The plunger 126 is movable in a bore 130 provided in a block-shaped deflector guiding member 132 which is secured on a rockshaft 134 by a set screw 136. The guiding member 132 is located between two downwardly extending spaced lugs 138 (Fig. 2) on the above mentioned bracket 24, the shaft 134 being rotatably mounted in both lugs 138. A rocking movement of the shaft 134 thus causes the guiding member 132 to move with relation to the lugs 138, thereby changing the position of the prongs 122 of the deflector 120, with the result that the curvature of the staple is changed. To this end, the shaft 134 has an enlarged portion 140 (Figs. 2 and 3)

integral with which is an upwardly extending bifurcated member 142. The member 142 engages an eccentric portion 144 of a rockshaft 146 the left hand end of which (Fig. 2) is arranged in a suitable bearing in the right hand lug 128. The right hand end (Fig. 2) of the rockshaft 146 is rotatable in a bracket 148 (Figs. 2 and 5) secured to the bracket 24 and supporting adjusting mechanism by means of which the shaft 146 may be rocked, this in turn rocking the shaft 134, with the results described. Secured to the shaft 146 is a handle 150 which serves to rock the shaft and carries a spring pressed locking plunger 152 arranged to engage notched stops 154 adjustably mounted on a segment 156 which is part of the bracket 148. Thus the range of adjusting movement of the handle 150 may be shifted or varied, the handle 150 being held in adjusted position by the stops 154. To make possible further adjustment of the deflector 120 in the extreme positions of adjustment of the handle 150, the latter is provided with a side bracket 158 in which is mounted a stub shaft 160. Splined to the stub shaft 160 is an auxiliary handle 162 by which the shaft 160 may be rotated. The shaft 160 carries a gear segment 164 which meshes with a gear segment 166 on the shaft 146. By rotation of the auxiliary handle 162, additional movement may thus be imparted to the shaft 146 so that an additional adjustment of the deflector 120 may be effected.

To move the deflector 120 heightwise of the machine and in a direction substantially at right angles to the bottom face of the sole member C into and out of engagement with the work, the following mechanism is provided. The guiding member 132 (Fig. 3) is reduced or slabbed off at its upper portion, thereby opening the bore 130 at opposite sides, to permit movement of a cross pin 158 carried by the upper portion of the plunger 120. The cross pin 158 extends beyond the opposite sides at the upper portion of the guiding member 132 into slots 170 provided in the tines of the bifurcated end of an arm 172 secured on a shaft 174 which is rotatable in lugs 176 provided on the bracket 24. To rotate the shaft 174, the left hand end of it (Fig. 2) has secured to it a forwardly and upwardly extending arm 178 which is pivotally connected to the bifurcated end of an arm 180 (Fig. 4) fulcrumed on the left hand portion (Fig. 2) of the shaft 78. A spring 182 (Fig. 4) connecting the arm 180 with a portion of the slide 18 tends to pull up the arm 180, thereby elevating the deflector 120. To depress the arm 180 for the purpose of lowering the deflector into the work, there is provided a deflector operating lever 184 fulcrumed on the left hand portion of the shaft 78. The lever 184 is provided with a cam track 186 (Fig. 1) which is engaged by a cam roll 188 carried by the forwardly extending arm of the bell crank lever 92 which, as above described, also serves to actuate the driver 56. The cam track 186 is so designed that, upon upward movement of the cam roll 188 therein, the deflector operating lever 184 is immediately rotated in a counterclockwise direction, as viewed in Fig. 1, this for the purpose of lowering the deflector 120 into the work. To this end, there is provided a latch connection between the lever 184 and the arm 180, the connection comprising a latch plate 190 (Figs. 1 and 4) secured to the arm 180 and a latch 192 in the shape of a bell crank lever pivotally secured to the lever 184. The downwardly extending arm of the latch 192 is arranged to engage the latch

plate 190 so that, upon movement of the lever 184 in a counterclockwise direction, the arm 180 is depressed to operate the deflector. For the purpose of breaking this latch connection after the deflector has entered the work and has served to curve the staple legs the rearwardly extending arm of the latch 192 is in engagement with a swivel block 194 carried on a rod 196 and secured in place by nuts and locknuts 198. The rod 196 connects the latch 192 with a trip arm 200 pivotally secured to the bell crank lever 92 and provided with a tail portion 202 adapted to be engaged by an extension 204 of the cam roll 188 near the upper end of the upward travel of the latter. To bring about latching engagement of the latch 192 with the latch plate 190, there is coiled about the hub of the latch 192 a torsion spring 206 one end of which bears against a pin on the downwardly extending arm of the latch 192 and the other end of which engages a portion of the deflector operating lever 184. As already mentioned, on upward movement of the cam roll 188 in the cam track 186, the deflector 120 is lowered to pierce through the overlasted marginal portion of the upper A and to enter the sole member C. Just before the completion of the upward movement of the roll 188, it strikes against the tail portion 202 of the trip arm 200 thereby lifting the arm and, through the agency of the rod 196, moving the latch 192 out of engagement with the latch plate 190 so that the spring 182, which has become tensioned as a result of the downward movement of the arm 180, is now free to pull the arm 180 up against a stop screw 208 carried by the slide extension 62. When the torsion spring 182, which actuates the bell crank lever 92, is loaded upon downward and forward movement of the slide 18, the roll 188 is moved downwardly in the cam track 186 and, as soon as it has moved out of engagement with the tail portion 202 of the trip arm 200, the torsion spring 206 is free to rotate the latch 192 back into latching engagement with the latch plate 190. The purpose of this arrangement is to insure that the deflector 120 enters the work immediately after the laying of the marginal portion of the upper on the sole member, accomplished by the downward and forward movement of the slide 18 and before the driver 56 is caused to drive the staple into the work. On the other hand, this arrangement insures that the deflector 120 is immediately withdrawn out of engagement with the work as soon as the staple is driven home and before the slide 18 is again retracted.

In the operation of the machine, the operator presents a work piece, comprising a last B with an upper A thereon and a sole member C, for example an insole, on the bottom face of the last, bottom up, to the machine in a position determined by the edge gage 12 and bottom rest 14 and inserts the marginal portion of the upper in the open gripper 10. When the machine is initially at rest the slide 18 is in its retracted rearward position and the downwardly extending arm 100 of the bell crank lever 92 is engaged by the latch 192 with the bell crank lever so positioned that the two cam rolls 96 and 188 carried by it are in their elevated positions. Consequently, the latch connection 190, 192 between the deflector operating lever 184 and the arm 180 is broken and the deflector 120 is up, the driver 56 still being in its lowermost position. After the initiation of a cycle of operations, the gripper 10 is closed upon the upper and is caused to pull the upper heightwise of the last and to draw the

marginal portion of the upper inwardly over the sole member, the gripper then holding the upper stressed until it is released at a later stage in the cycle.

A length of wire having been fed into the staple forming mechanism, the slide 18 is caused to move forward and downward toward the shoe bottom. This movement of the slide 18 is utilized to perform various operations. The throat comprising the plates 38 is carried inwardly over the edge of the shoe bottom, thereby engaging the tensioned marginal portion of the upper and laying it flat against the plane bottom face of the sole member in lasted relation thereto. Moreover, the length of wire which has been fed into the staple forming mechanism is severed from the wire strand by the knife to which it is presented by the slide 18. The inside former, carried by the slide, then pushes this length of wire into the stationary outside former to form a staple which thereafter is moved by the staple transferring member 34 into driving position in the throat. Finally, the bell crank lever 92, which is carried by the slide 18 and the downwardly extending arm 106 of which is held by the latch 110, is rotated in a clockwise direction, as viewed in Fig. 1, with the result that the spring 102 is loaded and the cam rolls 96 and 188 are lowered, thereby withdrawing or cocking the driver 56 and permitting the spring 206, as a result of the movement of the cam roll 188 away from the trip arm 206, to move the latch 192 into engagement with the latch plate 190 to establish driving connection between the deflector operating lever 184 and the arm 180. When the slide 18 has arrived at the end of its forward and downward travel, the cam rolls 96 and 188 are located substantially at the lower ends of their respective cam tracks 98 and 186 and the trip screw 116 is now in the immediate vicinity of the arm 118 of the latch 110. Counterclockwise rotation (as seen in Fig. 1) of the cam operated lever 112 then trips the latch 110, thereby releasing the bell crank lever 92 to the force of its loaded spring 102 which rotates the bell crank lever with great speed and force in a counterclockwise direction (Fig. 1). Consequently, the cam rolls 96 and 188 are elevated in their respective cam tracks 98 and 186.

Considering the elevation of the cam rolls 96 and 188 separately and beginning with the action of the cam roll 188, it will be remembered that the cam track 186 in the deflector operating lever 184 is of such shape that the lever 184 is immediately rotated in a counterclockwise direction causing, through the agency of the established connection between the latch 192 and the latch plate 190, a downward movement of the arm 180. This results in a downward movement of the arms 178 and 172 and of the deflector 120 which is caused to pierce through the overlasted marginal portion of the upper, preferably while it is still held tensioned by the gripper 10, and to enter the sole member as illustrated in Fig. 4. Thus the full tension imparted to the upper is maintained by the deflector having impaled the marginal portion of the upper.

Considering now the action of the cam roll 96, it will be remembered that the cam track 98 is designed to permit at first a short dwell in the clockwise movement of the driver operating lever 76 resulting from the upward movement of the cam roll 96, this to enable the staple transferring member 34 to move the formed staple to driving position in the throat and the deflector 120 to move into the staple deflecting position inside

the work. The driver 56 is then quickly moved down to drive the staple out of the throat into the work, the staple legs, after having entered the work, engaging the curved deflecting grooves provided in the prongs 122 of the deflector and being curled away from the edge of the sole member and upward toward the side of the work from which the staple entered it, without penetrating the entire thickness of the sole member.

It should be noted also that, as a result of the actual penetration of the deflector into the work, the work is effectively held by the deflector against the thrust of the staple driver when on its staple inserting stroke, thus essentially relieving the operator from the task of holding the work in proper position and against the work displacing force of the driver.

The staple having been completely inserted with its crossbar embedded in the work surface, the deflector is immediately withdrawn, as described, while the driver remains down on the work, thus barring any possibility of the deflector interfering with the proper location of the driven staple in the work upon its withdrawal from the work. As previously explained, the cam roll 188 on its upward travel finally engages the tail portion 202 of the trip arm 206 swinging this arm up and thus moving the latch 192 out of engagement with the latch plate 190, thereby enabling the spring 182 to pull the arm 136 up against the stop screw 208 and to withdraw the deflector from the work. The retraction of the slide 18 into its elevated rear position completes the cycle.

The holes made by the deflector 120 through the overlasted marginal portion of the upper and in the sole member are not objectionable since they are covered by the outsole after the latter has become attached to the shoe bottom. In fact, should it be desired to attach the outsole to the shoe bottom by cement, the holes made by the deflector are of considerable benefit since they permit the outsole attaching cement to penetrate through the overlasted marginal portion of the upper into the insole, thereby affording a cement bond of increased strength.

Having thus described my invention, what I claim as new and desire to secure by Letters Patent of the United States is:

1. A shoe lasting machine having, in combination, means for pulling a shoe upper over a last, means movable inwardly over the shoe bottom for laying the margin of the upper inwardly over the bottom face of a sole on the last, and means for fastening the upper comprising a fastening inserting driver and a work entering fastening deflector movable inwardly with said overlaying means and adapted to engage successive portions of a fastening after these portions have entered the work and to bend the fastening progressively in the driving operation to cause the fastening to become anchored in the work without penetrating the entire thickness thereof.

2. A shoe lasting machine having, in combination, means for pulling a shoe upper over a last, means movable inwardly over the shoe bottom for laying the margin of the upper inwardly over the bottom face of a sole on the last, and means for fastening the upper adapted to move inwardly with said overlaying means and comprising a fastening inserting driver and a work entering deflector adapted to engage successive portions of a fastening after these portions have entered the work and to bend the fastening progressively in the driving operation to cause the

fastening to become anchored in the work without penetrating the entire thickness thereof.

3. A shoe lasting machine having, in combination, means for pulling a shoe upper over a last, means for laying the tensioned marginal portion of the upper over the bottom face of a sole on the last, said overlaying means comprising a throat adapted to guide upper securing fastenings and movable in a direction inclined to the bottom face of the sole in the overlaying operation, a driver also movable in a direction inclined to the bottom face of the sole but different from the first mentioned direction to drive a fastening, and a work entering deflector mounted to move with said throat and adapted to engage successive portions of the fastening after these portions have entered the work and to bend the fastening progressively in the driving operation so as to cause the fastening to become anchored in the work without penetrating the entire thickness thereof.

4. A shoe lasting machine having, in combination, means for pulling a shoe upper over a last, means for laying the tensioned marginal portion of the upper over the bottom face of a sole on the last, said overlaying means comprising a throat adapted to guide upper securing fastenings and movable in a direction inclined to the bottom face of the sole in the overlaying operation, a driver also movable in a direction inclined to the bottom face of the sole but different from the first mentioned direction to drive a fastening, and a deflector mounted to move with said throat in the overlaying operation and thereafter to move in a different direction to enter the work, the deflector being adapted to engage successive portions of the fastening after these portions have entered the work and to bend the fastening progressively in the driving operation so as to cause the fastening to become anchored in the work without penetrating the entire thickness thereof.

5. A shoe lasting machine having, in combination, a driver for driving a staple into a sole on a last, a deflector arranged at the same side of the sole as the driver and operated to enter the sole prior to the staple driving operation, the deflector being arranged to deflect the staple legs laterally of the crossbar of the staple in curved paths of such radius as to cause the ends of the staple legs to turn toward said side of the sole, and an operating lever common to both the driver and the deflector.

6. A shoe lasting machine having, in combination, shoe positioning means, means for pulling the shoe upper over a last, and means for fastening the upper to a sole on the last bottom comprising a driver movable in a direction inclined outwardly toward the edge of the sole to drive a fastening through the upper and into the sole and a sole entering deflector arranged to engage different portions of the fastening successively in the driving operation after the different respective portions have entered the work so as to curve them inwardly away from the edge of the sole.

7. A shoe lasting machine having, in combination, shoe positioning means, upper fastening mechanism comprising a driver, a fastening guiding throat and a deflector movable together inwardly over the bottom of a shoe into position for fastening the upper to a sole, mechanism active thereafter for moving said deflector in a direction substantially normal to the sole into a position within the substance of the sole in which

it is adapted to bend a fastening progressively in the driving operation, and mechanism active thereafter for moving the driver in a direction inclined outwardly toward the adjacent edge of the sole to drive the fastening through the upper and into the sole.

10 8. A shoe lasting machine having, in combination, shoe positioning means, upper fastening mechanism comprising a driver, a fastening guiding throat and a deflector movable together inwardly over the bottom of a shoe into position for fastening the upper to a sole, a lever active thereafter for moving said deflector in a direction substantially normal to the sole into a position within the substance of the sole in which it is adapted to bend a fastening progressively in the driving operation, a lever for moving the driver in a direction inclined outwardly toward the adjacent edge of the sole to drive the fastening through the upper and into the sole, and a lever for operating both the aforementioned levers.

25 9. A shoe lasting machine having, in combination, shoe positioning means, upper fastening mechanism comprising a driver, a fastening guiding throat and a deflector movable together inwardly over the bottom of a shoe into position for fastening the upper to a sole, a lever having a cam track therein and adapted to move said deflector in a direction substantially normal to the sole into a position within the substance of the sole in which it is adapted to bend a fastening progressively in the driving operation, a lever having a cam track therein and adapted to move the driver in a direction inclined outwardly toward the adjacent edge of the sole to drive the fastening through the upper and into the sole, and a lever carrying rolls engaging said tracks to actuate the deflector and the driver.

40 10. A shoe lasting machine having, in combination, shoe positioning means, upper fastening mechanism comprising a deflector adapted to bend a fastening progressively in the driving operation and a fastening inserting driver, a slide movable inwardly over the bottom of a shoe to carry said deflector and driver into positions from which they may be operated, and means carried by said slide for operating the deflector to enter the sole so as to deflect the fastening within the substance of the sole and for operating said driver.

45 11. A shoe lasting machine having, in combination, shoe positioning means, upper fastening mechanism comprising a movable deflector adapted to bend a fastening progressively in the driving operation and a fastening inserting driver, a slide movable inwardly over the bottom of a shoe to carry said deflector and driver into positions from which they may be operated, and means active as a result of said movement of the slide to operate said deflector and driver.

50 12. A shoe lasting machine having, in combination, shoe positioning means, upper fastening mechanism comprising a deflector adapted to bend a fastening progressively in the driving operation and a fastening inserting driver, a slide movable inwardly over the bottom of a shoe to carry said deflector and driver into positions from which they may be operated, a lever on said slide for moving said deflector in a direction substantially normal to the bottom of the shoe into a position within the substance of a sole member in which position it is adapted to bend the fastening progressively in the driving operation, another lever on said slide for moving the driver in a direction inclined outwardly toward the adjacent edge of the sole member to

drive the fastening through the upper into the sole member, and a third lever on the slide for operating the aforementioned two levers in time relation to each other, the third lever being active as a result of said movement of the slide.

13. A shoe lasting machine having, in combination, shoe positioning means, upper fastening mechanism comprising a work entering staple deflector and a staple driver, driver operating means, and connections between said driver operating means and said deflector for operating the deflector in time relation to the driver.

14. A shoe lasting machine having, in combination, shoe positioning means, upper fastening mechanism comprising a work entering staple deflector and a staple driver, driver operating means, and connections between said driver operating means and said deflector causing the deflector to enter the work before the driver is operated to drive the staple into the work and to be withdrawn from the work before the driver is withdrawn.

15. A shoe lasting machine having, in combination, shoe positioning means, upper fastening mechanism comprising a staple deflector having two work entering prongs adapted to guide and deflect the staple legs within the work, a staple driver, driver operating means and connections between the driver operating means and the deflector for operating the deflector in time relation to the driver.

16. A shoe lasting machine having, in combination, shoe positioning means, upper fastening mechanism comprising a deflector adapted to bend a fastening progressively in the driving operation and a fastening inserting driver, a slide movable inwardly over the bottom of a shoe to carry said deflector and driver into positions from which they may be operated, a deflector guiding member on the slide adapted to guide the deflector to move in a direction substantially normal to the shoe bottom, means on the slide for operating the deflector to move to a position within the substance of a sole member of the shoe after the inward movement of the slide, and driver operating means adapted to actuate the deflector operating means in time relation to the operation of the driver.

17. A shoe lasting machine having, in combination, shoe positioning means, upper fastening mechanism comprising a work entering staple deflector and a staple driver, driver operating means, deflector operating means, and a latch connection between said driver operating means and deflector operating means, the latch connection being operative to cause the deflector to enter the work on actuation of the driver operating means.

18. A shoe lasting machine having, in combination, shoe positioning means, upper fastening mechanism comprising a work entering staple deflector and a staple driver, driver operating means, deflector operating means, a latch connection between said driver operating means and deflector operating means, the latch connection being operative to cause the deflector to enter the work on actuation of the driver operating means, means tending to withdraw the deflector from the work, and automatically controlled means adapted to break said latch connection immediately after the driving of a staple to cause the deflector to be withdrawn from the work.

19. A shoe lasting machine having, in combination, shoe positioning means, upper fastening mechanism comprising a work entering staple

deflector and a staple driver, driver operating means, deflector operating means, a latch connection between said driver operating means and deflector operating means, the latch connection being operative to cause the deflector to enter the work on actuation of the driver operating means, yielding means tending to render said latch connection operative, spring means tending to withdraw the deflector from the work, and means controlled by the deflector operating means to render said latch connection inoperative immediately after the driving of a staple to permit said spring means to withdraw the deflector from the work.

15. A shoe lasting machine having, in combination, shoe positioning means, upper fastening mechanism comprising a movable deflector adapted to curve a fastening progressively in the driving operation and a fastening inserting driver, a slide movable inwardly over the bottom of a shoe to carry said deflector and driver into positions from which they may be operated, a deflector guiding member pivotally mounted on the slide, means for adjusting said guiding member thereby adjusting the operative position of the deflector to vary the curvature imparted to the fastening, and means on the slide for operating the deflector to move to a position within the substance of a sole member of the shoe.

16. A shoe lasting machine having, in combination, shoe positioning means, means for pulling a shoe upper over a last and for laying the tensioned marginal portion of the upper over a sole on the last, upper fastening mechanism comprising a staple deflector adapted to pierce the tensioned marginal portion of the upper and to enter the sole and a staple driver, means for operating the deflector to enter the sole before the staple is driven into the sole so as to cause the deflector to hold the shoe against the operating thrust of the driver and to curve the staple legs within the sole, and means for operating the driver.

17. A shoe lasting machine having, in combination, shoe positioning means, means for pulling a shoe upper over a last and for laying the tensioned marginal portion of the upper over a sole on the last, upper fastening mechanism comprising a staple deflector adapted to pierce the tensioned marginal portion of the upper and to enter the sole and a staple driver, means for operating the deflector to enter the sole before the staple is driven into the sole so as to cause the deflector to hold the tensioned marginal portion of the upper in lasted relation to the sole and to support the shoe against the operating thrust of the driver, and means for operating the driver.

18. That improvement in methods of making shoes which consists in pulling a shoe upper successively in different locations along the sides of a shoe and laying its marginal portion inwardly over the margin of a sole in lasted relation thereto and, after each of the upper pulling and overlaying operations, temporarily holding the portion of the upper which is under lasting stress in lasted relation to the sole by inserting a fastening deflector through the upper and the bottom face of the sole into the intact substance of the sole, and securing said portion of the upper in lasted position by inserting a fastening through the upper and into the sole in such a way that successive portions of the fastening are successively deflected by said deflector within the substance of the sole.

24. That improvement in methods of making shoes which consists in pulling a shoe upper over a last and laying its marginal portion inwardly over the bottom face of a sole on the last, driving a staple through the marginal portion of the upper and into the sole by a force applied in a direction inclined outwardly toward the edge of the sole with the crossbar of the staple extending lengthwise of said edge, and engaging different portions of the legs of the staple successively in the driving operation after the different respective portions have entered the work, thereby to deflect them in curved paths leading inwardly away from the edge of the sole to anchor them within the substance of the sole. 15

25. That improvement in methods of making shoes which consists in pulling a shoe upper over a last and laying its marginal portion inwardly over the bottom face of a sole on the last, temporarily holding the margin of the upper while under lasting stress in lasted relation to the sole by inserting an awl having staple deflecting portions through the upper and into the sole, se- 20

5

curing the upper in lasted position by inserting a staple through the upper and into the sole in such a way that the staple legs, after having entered the work, strike against the staple deflecting portions of the awl and become deflected, thereby anchoring the staple within the substance of the sole, and embedding the crossbar of the staple in the exposed surface of said margin of the upper.
